[57] CLAIM

The ornamental design for mounting bracket for a flush-mounted latch assembly, as shown and described.

DESCRIPTION

FIG. 1 is a top perspective view of a mounting bracket for a flush-mounted latch assembly showing our new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof;

FIG. 7 is a left side elevational view thereof; and,

FIG. 8 is a bottom perspective view thereof, the broken-line showing of a latch assembly being for illustrative purposes only and forming no part of the claimed design.

FIG. 1

FIG. 2

FIG. 3

FIG. 4

FIG. 5

FIG. 6

FIG. 7

FIG. 8
